WELDER'S MASK

Frederick M. Bowers, Chester, Pa.

Application December 4, 1931. Serial No. 578,895

5 Claims. (Cl. 2—8)

This invention relates to welders' masks, and has for an object to provide a welder's mask having a sight opening therethrough, with means for supporting the transparent sheet forming such sight opening, and presenting upon the anterior of said mask no metallic parts.

In the use of a welder's mask, it is well known that metallic elements at the anterior of said mask subject to the influences of the welding operation are objectionable, and especially if such metallic elements pass entirely through the welder's mask as they are conductive of heat and under some conditions, as well, conductive of electric current.

15 The present invention, therefore, is directed to the formation of a welder's mask of sheet material of a non-conductive nature, upon the anterior of which is positioned a frame of non-conductive material secured to the sheet material 20 from the interior of the mask, and with improved means for maintaining a transparent sheet in the frame.

The invention is directed to other objects and possesses other features of novelty and advantage, some of which, together with the foregoing, will be hereinafter more fully set forth.

In the drawing:

Figure 1 is a view of a fragment of the anterior part of a welder's mask seen in side elevation, with the frame member seen in end elevation,

30 Figure 2 is a view of a fragment of a mask in front elevation, as indicated by arrow 2 at Figure 1,

35 Figure 3 is a longitudinal sectional view through the frame and adjacent structure, as taken on line 3—3 of Figure 2,

Figure 4 is a transverse sectional view through the frame and adjacent structure as on line 4—4 of Figure 2,

40 Figure 5 is a detail view partly in end elevation and partly in section of the follower for the interior of the mask, and

45 Figure 6 is a perspective view of the angle employed to engage the spring used in holding the transparent sheet in position.

Like characters of reference indicate corresponding parts throughout the several views.

The improved welder's mask, which forms the 50 subject matter of this application comprises a sheet of material 10 curved to the usual form of such masks, presenting an arcuate anterior portion. The anterior portion is provided with a cut-out about which a frame 11 is secured.

55 This frame 11 is preferably molded of some

non-conductive material, as for instance, bakelite, although the invention is in no way limited to the particular material. The frame member has an inturned flange 12, upon which is seated, the transparent sheet 13 which may and in most cases will be of glass. The opening in the frame member in which the glass is inserted corresponds to and registers with the opening in the sheet 10.

A follower 14 is properly proportioned to be 65 inserted through the opening of the mask and within the frame 11. The glass 13 is of such proportion as to lie within this follower when in position, as indicated at Figures 3 and 4. The ends of the follower are formed bevelled as shown 70 at 15 in Figure 3 to correspond to the curvature of the sheet 10 and an angle 16 is inserted within this follower, and the entire organization formed into a unitary structure as by the screws 17 passing through the openings 18 in the angle and 75 through the bevelled end 15 of the follower 14 and into the frame 11.

The follower is provided with an opening 19 at each end, and the angle is provided with a slot 20 registering with the opening 19 of the 80 follower.

A spring 21 has ears 22 at the ends extending through the slot 20 of the angle and into the opening 19 of the follower. This spring is substantially the type shown in applicant's prior 85 patents and applications and is not specific to the present invention, except to the formation of the ears 22 at the ends. It occupies a bowed position as shown at Figures 3 and 4, the central part of which is provided with a slit forming a 90 tongue 23 which bears upon the transparent sheet 13. When moved to dotted line position as shown at Figure 3, the transparent sheet may be removed from the frame without the necessity of removing the spring bodily from the supporting 95 structure.

It will be noted that the only metallic parts of the structure are within the curvature of the sheet 10, and are, therefore, wholly insulated from the welding operation which is performed, 100 of course, upon the exterior of said mask.

Of course, the welder's mask, herein illustrated may be modified in various ways without departing from the invention herein set forth and hereinafter claimed.

The invention is hereby claimed as follows:

1. A welder's mask comprising an arcuate body part having an opening, a frame member of insulating material having an arcuate part fitting upon the anterior of the arc and having an open-

ing registering with the opening of the body, means having also a registering opening within the arc for securing the frame rigidly to the body part, and means including said last mentioned 5 means to maintain a transparent sheet yieldingly within the securing means.

2. A welder's mask comprising an arcuate body having an opening in the anterior part, a frame of insulating material upon the anterior surface 10 of the arc and having an opening registering with the opening of the body, a follower within the arc inserted through the opening of the arcuate body and into the frame, and penetrating means inserted through said follower, 15 through the arcuate body and into the posterior side of the frame.

3. A welder's mask comprising an arcuate body having an opening in the anterior part, a frame of molded insulating material having a 20 part curved to fit the arcuate body and with a relatively plane anterior side, said frame presenting an opening registering with the opening of the body and having an inturned flange, a follower within the body, penetrating means inserted through the follower and the arcuate body into the frame, and means within the frame for 25 maintaining a transparent sheet within the follower upon the inturned flange.

4. A welder's mask comprising an arcuate body of sheet material having an opening through the anterior part thereof, a frame of

molded insulating material upon and corresponding with the arcuate exterior and presenting a relatively plain anterior part, said plain part being provided with an opening having an in-turned flange, a follower within the arcuate body having a part inserted through said body and into said frame and with parts extending outwardly over the margins of said arcuate body, penetrating means extending through the outwardly extending parts through the arcuate body and into the frame from the interior, and means fitted within the follower to maintain a transparent sheet upon the inturned flanges of the frame.

5. A welder's mask comprising an arcuate sheet of material having an opening therein, a molded frame of insulating material upon the exterior of said arcuate body, said frame comprising an opening having an inturned flange, a follower within the arcuate body inserted through said opening and into the frame and clamping the margins of the material therebetween, an angle secured upon said follower and having one flange extended downwardly within said follower and provided with an opening, and a spring retainer having ears inserted in said opening and its intermediate part bowed into position for clamping a sheet of transparent material upon the flange of the frame.
